VACUUM-TUBE BASE.

Application filed May 7, 1926. Serial No. 107,328.

Our invention relates to vacuum tube devices and particularly to base devices therefor.

An object of our invention is to provide a base for a vacuum tube structure, adapted to facilitate the insertion of the tube into a standard socket, and the connection thereto of special current supplies.

Another object of our invention is to provide a special base for a vacuum tube, adapted to facilitate the utilization of tubes capable of translating higher powers, and the connection thereto of additional extra voltage sources.

Another object of our invention is to provide a base for a high power vacuum tube for signal receiving apparatus, adapted to cooperate with existing circuits and sockets and to provide means for the connection 20 of the additional voltage sources without change of existing wiring and circuits.

Another object of our invention is to provide a base for a vacuum tube device having therein the customary connection prongs, 25 and also additional circuit connection members.

Another object of our invention is to provide an article of manufacture comprising a vacuum tube base of such simple construction that additional features are provided 30 without increase of manufacture costs and without exceeding the present standard dimensions.

In the development of the art of radio receiving it has been found desirable to provide, in certain electrical systems, vacuum tubes adapted to utilization with higher plate and grid voltages, and higher powers than other tubes in the same system and to 40 insert such higher power tubes in the place of previously used smaller tubes in the existing radio receiver apparatus. It has been found desirable to employ the same filament heating source and to utilize the same plate and grid batteries as are employed with the 45 other tubes in the set. It is also desirable to provide additional plate and grid voltage for supplying the power tube only. Likewise it is undesirable, and some times difficult, to modify the wiring already built in to the receiver apparatus, for connecting in the additional voltage to the power tube.

Our invention provides a simple, compact, inexpensive, base member adapted to cooperate with the power tube, adapted to be

inserted within an existing vacuum tube socket, and to embody in its construction the usual means for making connection to the existing circuits of the receiver, and additional means for connecting in the extra required batteries without change of the existing wiring. The device of my invention is a base member adapted to be attached to the power tube, to be inserted in an existing vacuum tube socket, and to carry additional 60 terminal members, without exceeding the overall dimensions of the usual tube.

By means of our invention we are enabled to provide a special base for a vacuum tube device, adapted to permit the insertion thereof into any existing tube socket and the simultaneous connection thereto only of additional auxiliary current sources and to utilize existing current sources also, without changes in existing circuits and without exceeding a size which is conveniently usable 70 with existing apparatus.

Other objects and structural details of our invention will be apparent from the following description when read in connection 80 with the accompanying drawing, wherein:

Figure 1 is a view in vertical elevation, partly in section of an embodiment of the device of our invention,

Figure 2 is a view partly in section at the 85 line II, of the same embodiment,

Figure 3 is a vertical sectional view of the base member of the same embodiment of our invention,

Figure 4 is a plan view of the embodiment 90 of Figure 3,

Figure 5 is a bottom view of the embodiment of Figure 3 and,

Figure 6 is a view in vertical elevation and partly in section of an alternative embodiment of our invention.

Referring to the figures, we provide a socket 1, which may preferably be of molded material composition, adapted to receive and be attached to the seal member end of a 100 vacuum tube device 2 and to be inserted in a socket 3. Referring particularly to Figure 1, the base member 1 consists of a cylindrical portion 4 and a closed end portion 5. Contact prong members 6 are attached to the end member 5, and serve to make connection with contact springs in the socket member 3 in the usual manner. A supporting member 7, which may be a collar as shown, or may be a series of lugs is at- 110

tached to or formed integrally with, the cylindrical portion 4 and provided with openings 9 adapted to carry terminal members 8. The holes 9 in the collar 7 may conveniently be counter-sunk and additional openings 10 provided from the interior of the cylindrical portion 4 to the counter-sunk portions 9. Access is thus provided for conductor members 11 and 12 leading from the 10 prong members 6 and the tube elements of the tube 2 to the terminal members 8. This construction provides means for secreting the connector wires within the base structure, and for preventing short circuit between them.

The preferred embodiment of our invention as shown in the figures is formed of an integral body of molded composition which may be of the bakelite type or of the shellac 20 type, and may be molded in the customary steel molds. The molds may comprise the usual split portions, one having a cup opening with an annular rim portion and the other a plunger to form the cup portion 4 25 of the base and the collar portion 7 thereon. Openings may be provided for carrying the lug members in the collar portion 7 by the embodiment of suitable plugs in the molded member in which the annular ring to 30 produce the collar 7 is formed. By this means the base member may be molded in an integral piece to which the auxiliary connector members are easily added and in which the necessary connector wires are 35 easily placed.

Alternatively the base member may be made of metal, stamped, drawn or rolled or otherwise formed, in which case lugs may be formed upon the rim. In this embodiment insulating bushings must be provided between the connector members and the metal base.

The length of the tubular portion 4 is conveniently made such that the distance 45 from the free end of the prong members 6 to the under surface of the collar portion 7 is slightly greater than the standard distance from the contact springs of the standard socket to the upper edge thereof, and the outer diameter of the collar member 7 may be equal to or only slightly greater than the maximum diameter of the tube portion 2.

Connections may be made between the 55 prong members 6, the vacuum tube electrodes, and the terminal members 8 as shown in the plan view of Figure 2, whereby the filament leads are directly connected to the proper prong members, the grid lead prong and the grid lead are respectively connected to one pair of the binding posts 8 and the plate lead prong and the plate lead are connected to the other pair of binding posts 8. By this means the additional grid voltage required for the power tube may be conveniently provided and connected between

the pair of terminals 8 marked C+ and C- and thereby in series with the vibratory current input and other C battery voltage through the socket contact spring. The additional plate voltage is conveniently connected to the binding posts 8 marked B+ and B- and thereby in series with the output device of the tube, and with the other B battery voltage supply.

Alternatively the well known Fahnstock 7 connectors or other terminal connectors may be used, in which case the collar 7 may be dispensed with and the connectors mounted directly upon the tubular portion 4 as shown in the embodiment illustrated in Figure 6. 81

By this means we are enabled to provide a power vacuum tube with special base member adapted for insertion directly into the standard vacuum tube socket, having contact members adapted to make connection 84 therein and having additional conductor members for the convenient connection of additional power supplies without disturbance of the wiring to the standard socket, in a space which permits insertion of the 90 tube structure within the usual vacuum tube apparatus.

While we have shown but two embodiments of our invention in the foregoing drawings and descriptions it is capable of 95 various modifications therefrom without departing from the spirit thereof, and it is desired therefore that only such limitations shall be imposed thereon as are required by the prior art or indicated by the appended 10 claims.

We claim as our invention:

1. A base for a vacuum tube device, comprising a tubular portion having terminals at an end thereof and a collar portion having 10 auxiliary terminals thereon.

2. A base for a vacuum tube device, comprising a cup shaped portion having prongs in the bottom thereof, a collar around the top thereof, and terminal members insulat- 110 ingly attached to said collar.

3. A base for a vacuum tube device, comprising a cup shaped portion, and a projecting member on the edge thereof, prongs attached to the bottom thereof, auxiliary terminals in said projecting member, and connector means between certain of said prongs and certain of said terminals.

4. A vacuum tube device, comprising a tube portion having electrodes and a base 120 portion of insulating material having contact prongs at an end thereof, certain thereof being attached to said vacuum tube electrodes, a projecting member, and connector members thereon, certain thereof being connected to said prongs and others thereof being connected to said tube electrodes.

5. A base for a vacuum tube device, comprising a cup shaped member having prongs in the bottom thereof, and an auxiliary con- 130

nection terminal supporting means integral therewith and projecting laterally therefrom.

6. A base for a vacuum tube device, comprising a cup shaped member having prongs, 5 connection terminal supporting means integral therewith and projecting laterally therefrom, and auxiliary connection terminals thereon.

7. A base for a vacuum tube device, comprising a cup shaped portion, prongs attached to the bottom thereof, a terminal supporting means and auxiliary terminals thereon, connector means between certain of 10 said prongs and certain of said terminals, 15 and means including openings in the body of said base for housing said connector means.

8. A vacuum tube base member, comprising an integral member of plastic material, 20 having a cup shaped portion, terminals in the bottom thereof and a projecting means for supporting a connection terminal, with 25 openings therein for connector members.

9. A vacuum tube device, comprising a 30 bulb member having electrodes adapted for the translation of superior degrees of power, and a base portion adapted for the connection thereto of auxiliary power sources and comprising a cup shaped portion having 35 prongs thereon, an auxiliary contact supporting means, and connecting means thereon adapted for the connection of said additional power sources in series between said prongs and said vacuum tube electrodes.

35 10. A vacuum tube device, comprising a bulb member having electrodes adapted for the translation of superior degrees of power,

and a base portion adapted for the connection thereto of auxiliary power sources and comprising a cup shaped portion having 40 prongs thereon, an auxiliary contact supporting means, connecting means thereon adapted for the connection of said additional power sources in series between said prongs and 45 said vacuum tube electrodes, connector means between said prongs and said auxiliary terminals, and means including openings in said cup for housing said connectors adjacent the glass of said bulb member.

11. A vacuum tube base comprising a cup- 50 shaped portion having a rim and bottom, four contact making prongs attached to the bottom thereof, a projecting member at said rim, four auxiliary connectors insulatingly positioned thereon, and connections between 55 said prongs and said connectors.

12. A thermionic tube including anode, cathode and modulating elements, base for 60 said tube, terminal connections for the several elements carried by the base, lead conductors intermediate the terminal connections and 65 said elements, and spaced auxiliary terminals in the lead conductors pertaining to the anode and modulating elements, across which accessory devices may be connected into the anode and modulating circuits.

13. In a thermionic valve, including a grid element, a main electrical contact terminal and means for bridging an auxiliary grid biasing battery intermediate the grid element 70 and terminal.
